UNITED STATES PATENT OFFICE.

JOSEPH GREENBERG, OF NEWARK, NEW JERSEY.

STERILIZING APPARATUS.

Application filed May 4, 1927. Serial No. 188,845.

This invention relates to a sterilizing apparatus for use in places such as fountains, restaurants, and the like and I illustrate one such as would be used as part of the fixtures 5 of soda fountains where a quick washing and sterilizing of glasses, cups, plates and similar articles is performed in the interval between successive uses by customers.

The custom has been to simply wash the 10 dishes in a small tank of hot water and allow them to drain and then again use them. The present device includes a tank in which the utensils and dishes can be placed in boiling water to completely sterilize them 15 and this tank is subjected to the action of flame and also the dropping therein of fairly heavy articles. The repair and sealing of this tank is made necessary much more frequently than in an ordinary hot water tank.

20 The time necessary for repair is shortened by making this sterilizing tank easily removable so that a tank can be disconnected and another tank put in its place and connected up and the old tank taken away for soldering 25 or other repair work necessary. The time consumed to the user is only that necessary in removing one tank and installing another and the operation of the lunch counter or other equipment where the tank is used is 30 only momentarily interrupted.

The invention will be better understood by reference to the accompanying drawing which shows one embodiment of my invention. Figure 1 is a face view of an installation showing the usual washing tank and the additional sterilizing tank, the latter and part of the former being shown in section. 35 Figure 2 is a perspective view of the sterilizing tank shown in Figure 1. Figure 3 is a 40 perspective view of a casing in which the burner is placed underneath the sterilizing tank.

The drawing shows a conventional wash tank 10 which is supported by the frame 11 45 and has an outlet 12 and the usual hot water faucet 13 and the cold water faucet 14. So far as described this is the usual form of ordinary dish washing tank installed behind the counter of soda fountains and the

like. However, with the growing custom 50 of quick lunches at such counters the necessity of complete sterilization is pronounced and for this purpose I attach a semi-detachable sterilizing tank.

In the form illustrated the sterilizing tank 55 is shown at 15 and it is usually made the same size as the tank 10. The sterilizing tank is provided with a means for lifting it, as the flange 16 which is also used as a part 60 of the support as it rests on the marginal rail 17 of the support and on the edge of the partition 17^a which forms one wall of the tank 10 although when the tank 15 is used alone the marginal rail 17 is extended no further than the edges of the tank 15.

65 The tank 15 is usually supplied with a rear upwardly extension 18 which is a continuation of the back wall 19 of the tank. The extension has a flange 20 which rests on the top edge of the wall 21 of the support.

70 The extension 18 has a hole 22 which receives the inlet pipe to which the faucet 23 is attached. The bottom of the support under the tank 15 is open for the purpose of allowing the heat from the burner 24 to be applied directly to the tank. The support is therefore open at the bottom and the burner is shown surrounded by a casing 25 which is provided with flanges 26 that slide 75 in the guides 27, and has the holes 28 for supplying air to the burner and the hole 29 for the passage of the gas pipe 30.

80 The outlet pipe 31 has a union connection 32 which is on the bottom of the tank and acts as a waste pipe with the usual stopper 85 33.

85 A small sliding door 34 in the front of the burner casing 25 provides a convenient opening for lighting the burner 24.

90 This construction allows a constant boiling or rather a sterilizing temperature in the sterilizing tank and this tank requires more or less frequent mending and repairing especially on the bottom. When this is necessary all that is to be done is to remove the 95 faucet 23 and unscrew the connection 32 and the tank can be lifted out and repaired and then put back or another tank of the same

construction can be quickly installed as a substitute. In this way the constant maintenance of tanks of this sort is possible.

Various changes of construction can be made without departing from the scope of the invention.

I claim:

A sterilizing apparatus comprising a sup-

port, a tank fitting in the support, and having a rear upward extension to support a faucet, and a waste pipe connection on the bottom of the tank said tank being removable when the faucet and waste pipe are disconnected.

In testimony whereof I affix my signature.

JOSEPH GREENBERG.
